United States Patent Office

Des. 182,712
Patented May 6, 1958

182,712

FOOD CONTAINER OR THE LIKE

Jack M. Dinken, Tokyo, Japan

Application June 21, 1957, Serial No. 46,681

Claims priority, application Japan March 6, 1957

Term of patent 7 years

(Cl. D58—11)

FIG. 1

FIG. 3

FIG. 2

FIG. 4

Fig. 1 is a front elevational view of a food container or the like, showing my new design;

Fig. 2 is a side elevational view thereof;

Fig. 3 is a top plan view thereof; and

Fig. 4 is a bottom plan view thereof.

The side not shown is the same as the side shown. The rear is substantially like the front with the figure omitted.

What I claim is:

The ornamental design for a food container or the like, substantially as shown and described.
